UNITED STATES PATENT OFFICE.

MARGARET M. J. ROONEY, OF NEW YORK, N. Y.

DESIGN FOR A CRUMB-TRAY.

No. 37,795.

Specification for Design.

Patented Jan. 23, 1906.

Application filed April 27, 1905. Serial No. 257,781. Term of patent 14 years.

To all whom it may concern:

Be it known that I, MARGARET M. J. ROONEY, a citizen of the United States, residing in the city, county, and State of New York, have invented a new, original, and ornamental Design for a Crumb-Tray, of which the following is a specification, reference being had to the accompanying drawing, forming a part thereof.

The drawing shows the crumb-tray in plan.
I claim—

The ornamental design for a crumb-tray, as shown.

MARGARET M. J. ROONEY.
